UNITED STATES PATENT OFFICE.

ALBERT DELMER COWDEN, OF WATERFORD, CALIFORNIA.

CAR-INDICATOR.

1,121,614.

Specification of Letters Patent.

Patented Dec. 22, 1914.

Application filed November 24, 1911. Serial No. 662,229.

To all whom it may concern:

Be it known that I, ALBERT D. COWDEN, a citizen of the United States, residing at Waterford, in the county of Stanislaus and 5 State of California, have invented a new and useful Car-Indicator, of which the following is a specification.

The present invention relates to improvements in car indicators, one object of the 10 invention being the provision of an indicator or tallying medium, whereby the station agent or freight agent may readily tally the cars under his direct supervision, both as to "local" and "foreign" cars, 15 local cars meaning the cars controlled by the railroad employing such agent, while the foreign cars are the cars owned and controlled by other roads, such indicator being so disposed and operated as to give the 20 total number of the various classes and kind of freight cars, and whether loaded or empty, together with the proper symbols, or numbers if desired, for carrying such totals to the proper column of the telegraphic car report, it being the prime object 25 of this invention to make it an easy matter to assemble all cars at a station under the proper symbol to be transmitted by telegraph to the superintendent's office, 30 or other main office.

With the foregoing and other objects in view which will appear as the description proceeds, the invention resides in the combination and arrangement of parts and in 35 the details of construction hereinafter described and claimed, it being understood that changes in the precise embodiment of the invention herein disclosed can be made within the scope of what is claimed without 40 departing from the spirit of the invention.

In the drawings is illustrated a perspective view of the upper end of the present car indicator, showing that the single leaf may be opened to cover either portion of 45 the stiff back.

Referring to the drawings, the base plate 5 is provided with a local index 6 and with a foreign index 8, while hingedly connected to form a hinge as at 7 is the leaf 7', carrying upon the outer face as exhibited the "foreign" index, and upon the face 10, the edge of which only is presented is an index 50 similar to the index 9, for correlation with the "local" index 6. This form of car index is especially adapted to be used as a

handy and ready means for giving the proper symbols of the various cars. With the yard book in one hand, and this little book in the other, the cars may be readily traced through the diagram, leading the operator to the proper symbol. These symbols may be noted after each car in the yard book, or tallied out on slips of paper, or in any way found convenient to the operator using the same.

In further describing the index and the operation thereof, it is to be noted that the indices 6 and 8 are provided under the respective heads of "Local" and "Foreign," the following parenthetical notations, to wit:—"Box" sub-divided into "Large" and "Small" further sub-divided respectively into "Loaded" and "Empty," the telegraphic code for each being disposed adjacent the respective words "Loaded" and "Empty." When the leaf 8 is disposed to rest upon and conceal the "local" index 6, there will be in correlation to the word "Large," the two words "Loaded" and "Empty," each one of which has its particular symbol and as therein illustrated C indicating "loaded," BZ indicating "empty." Thus the symbol C would indicate that there was a "loaded large box car" and that such box car was a "foreign" car. By this means, the various numbers and classes of cars may be checked, and when entered in the yard book or when telegraphic report is made thereon, it is merely necessary for the operator to telegraph 10 C to indicate that there is at his freight yard 10 loaded large foreign box cars.

What is claimed is:

1. An indicator for "local" and "foreign" cars, comprising a book of one leaf of relatively stiff material and a flat relatively stiff back, the leaf being hinged to swing to cover one portion of the back at a time, one portion of the back and the corresponding portion of the leaf being provided each with a series of terms for "local" or "foreign" cars, such terms being descriptive of some broad characteristic of a car, and the remaining portions of the leaf and back for correlation with the terms for "local" and "foreign" cars being provided with qualifying terms descriptive of the car, such qualifying terms being so disposed as to correlate with the respective 100 105 110

"local" or "foreign" terms according to the position of the leaf relatively to the back.

2. A car indicator, comprising a book of 5 one leaf and a flat relatively stiff back, the leaf being relatively stiff and hinged so as to swing to cover one portion of the back at a time, one portion of the back at one side of the hinge line of the leaf being provided 10 with a series of terms for "local" cars, such series of terms being descriptive of some broad characteristic of a car, while similar terms for "foreign" cars are disposed upon 15 the side of the leaf that lies flat upon to conceal the other side portion of the back, there being provided upon the remaining

side of the leaf for correlation with the "local" terms and upon the portion of the back to the right of the hinge for correlation with the "foreign" terms, qualifying 20 terms descriptive of the car, such qualifying terms being so disposed as to correlate with the respective "local" and "foreign" terms according to the position of the leaf relatively to the back. 25

In testimony that I claim the foregoing as my own, I have hereto affixed my signature in the presence of two witnesses.

ALBERT DELMER COWDEN.
